REFRIGERATOR DOOR SHELF CONSTRUCTION

Herbert D. Squire, Galesburg, Ill., assignor to Admiral Corporation, Chicago, Ill., a corporation of Delaware

Application February 7, 1957, Serial No. 638,871

2 Claims. (Cl. 312—214)

This invention relates to refrigerators and more particularly to refrigerator door shelves.

It has previously been proposed to provide shelves for a recess formed in the inner panel of a door of a refrigerator and which are arranged to support certain articles such as bottles, eggs and the like, thus providing greater storage capacity. In some instances these shelves are formed integral with the inner liner of the door which, although satisfactory, has the disadvantage that the shelves may not be spaced properly for the support of certain articles. Although to the best of my knowledge adjustable shelves have been previously contemplated, the means for adjustment was relatively difficult, rendered the shelves somewhat unstable in their attachment and frequently left unsightly openings where there were no shelves in which dirt and moisture could accumulate and which were particularly difficult to clean.

By the present invention I have provided a shelf construction in which various types of shelves may be used and wherein the height of the shelves may be adjusted within wide latitude in a manner so simple that it may be accomplished by persons of limited mechanical experience. The construction is such that regardless of the position to which the shelves are adjusted or the number of shelves used, the structure provides a finished and permanent appearance which does not detract from its aesthetic beauty.

Still other advantages of the invention and the invention itself will become more apparent from the following description of an embodiment thereof, which description is illustrated by the accompanying drawings and forms a part of this specification.

In the drawings:

Fig. 1 is a vertical elevational view of the inside of a refrigerator door removed from the cabinet, certain parts being broken away to show the construction of the parts below;

Figs. 2 and 3 are vertical front and side elevational views of a removable rail used in conjunction with the shelves;

Fig. 4 is a section taken on the line 4—4 of Fig. 2; and

Figs. 5, 6 and 7 are sections taken on lines 5—5, 6—6 and 7—7 of Fig. 1.

Briefly, the invention is used in conjunction with a refrigerator door having a recess in the inner face thereof of which is bounded by a pair of vertically extending plane surfaces having openings therein into which lugs carried by the shelves may extend and wherein rails are removably attached to the upper and lower ends and engage the shelves to hold them in position and conceal the openings.

More particularly as shown in Fig. 1 there is illustrated the door 10 having the usual peripheral gasket 11 and an inner recess 12 bounded by a rectangular flat surface or rib 13. The vertical reaches of the rib 13 at opposite edges of the door are provided with a plurality of vertically spaced apertures 14. Both of the side ribs have these apertures which are in alignment with each other.

2

As shown in Fig. 7 various types of shelves may be used. The upper shelf 20 is relatively deep. Disposed below the upper shelf is a shallow shelf 21 which operates in conjunction with a guard rail 22.

As best shown in Fig. 6, each of the shelves is provided with a rear surface 30 which conforms in contour to a horizontal section taken through the door. The shelf proper spans the intermediate portion of the door and the portion 30 is provided with laterally extending portions 31 from which rearwardly extending hook-shaped lugs 32 protrude. These lugs are adapted to be inserted through the apertures 14 in the door and then the entire shelf moved to cause the lugs to interlock with the lower edges of the openings 14.

Although the above description is the preferred form of locking the shelves in the apertures, it will be apparent with this construction that the lugs 32 need not necessarily be hook-shaped, but may be straight; providing the hook-shape facilitates the assembly thereof.

It is to be understood that each one of the shelves such as 20, 21 and 22 is provided with such rearwardly extending lugs which thus enable a shelf structure to be assembled in any desired manner by the user to best suit his needs.

For instance as shown in Figs. 7 and 1, should it be desired to store bottles, a shelf 21 with a relatively narrow vertical flange may be used, and, spaced at any desired distance above that shelf, is a guard rail 22 which is secured to the door in the same manner. It will be apparent that the shelves having been assembled the only holding means for the shelves described up to this point are the lugs 32. The unused apertures are open and unsightly.

Means is therefore provided for locking the shelves in place and for covering the unused apertures. It comprises an upper socket 40, Figs. 1 and 5, which is an inverted cup. A lug or pin 41 extends rearwardly from the socket and through a hole in the rib 13. A suitable locking device 42 is disposed on the pin for holding the socket in place. In this position it will be noted that the socket is inverted with the entrance in a downward direction. Likewise on the lower end of the rib 13 there is provided an upwardly opening socket 45. A rail member 48, Figs. 2, 3 and 4, is provided being of generally channel shape and having an upper curved end 49 for insertion in the upper socket and a lower square end 50 for engagement in the lower socket. Once the shelves are in position the rail 49 may be inserted in the socket 40, the rail slid upwardly in the socket and then swung inwardly until the bottom end is in alignment with the socket 45. It is then lowered into position into the socket 45 where it is seated. As shown in Fig. 4 the rail engages the lateral extension 31 of the shelves, retaining them in position in the apertures and at the same time, as best seen on the left side of Fig. 1, hides the unused apertures from view.

Having thus described my invention, I am aware that numerous and extensive departures may be made therefrom without departing from the scope of my invention as defined in the appended claims.

I claim:

1. A refrigerator door and shelf assembly comprising a refrigerator door having at its inner face an inwardly disposed recess and a pair of outwardly disposed, vertically extending flat ribs at opposite sides of said recess, said ribs having a plurality of pairs of vertically spaced apertures therein which open at the inner face of the door, the apertures of each pair being horizontally aligned with each other at opposite sides of said recess in the door, a plurality of shelves received in said recess in the door and spaced vertically one above the other, each of

said shelves carrying a pair of projections which are detachably received respectively in a corresponding pair of the apertures in the ribs at the opposite sides of said recess, said projections constituting the sole means of attachment of the respective shelves to the door, the number of said shelves being less than the number of pairs of said apertures to leave certain of said apertures open at the inner face of the door, a pair of retainer members which extend down across the respective ribs at the inner face of the door and present continuous unbroken outer surfaces which overlie all of said apertures in the ribs and said shelf projections, said retainer members being separate from the door and retaining said shelves in place with said projections received in the corresponding apertures in said ribs on the door, a pair of upper sockets mounted respectively on said ribs above the apertures therein, said upper sockets having downwardly facing openings which are closed at their upper ends and which slidably receive the upper ends of said retainer members, and a pair of lower sockets mounted respectively on said ribs below the apertures therein, said lower sockets having upwardly facing openings which are closed at their lower ends and which slidably receive the lower ends of said retainer members, the closed upper ends of the upper sockets being spaced from the lower sockets a distance greater than the length of the respective retainer members to permit the manual insertion and removal of the retainer members, said upper and lower sockets forming the sole means holding the retainer members in place overlying said ribs on the inner face of the door.

2. A refrigerator door and shelf assembly comprising a refrigerator door having at its inner face a pair of spaced downwardly extending ribs, said ribs having a plu-

10 rality of pairs of vertically spaced apertures therein which open at the inner face of the door, a plurality of shelves positioned at the inner face of the door and spaced vertically one above the other, each of said shelves carrying a pair of projections which are detachably received respectively in the apertures in the ribs at the opposite sides of said recess, the number of said shelves being less than the number of pairs of said apertures to leave certain of said apertures open at the inner face of the door, 15 a pair of retainer members which extend down across the respective ribs at the inner face of the door and overlie all of said apertures in the ribs and said shelf projections, supporting means for supporting said retainer members in place at the inner face of the door, said retainer members being manually removable from said supporting means, said supporting means for each retainer member comprising an upper socket attached to the inner face of the door above the apertures in the corresponding rib and having a downwardly facing opening which slidably receives the upper end of the respective retainer member, and a lower socket attached to the inner face of the door below the apertures in said rib and having an upwardly facing opening which slidably receives each retainer member having its outer surface unobstructed throughout its 20 extent between said upper and lower sockets.
